ERNEST JAMES SMITH, OF FLEET STREET, LONDON, ENGLAND, ASSIGNOR TO GOSS
PRINTING PRESS COMPANY, A CORPORATION OF ILLINOIS

SHEET CUTTING AND HANDLING MECHANISM

Application filed June 13, 1929. Serial No. 370,605.

The invention relates to new and useful improvements in sheet cutting, associating and folding mechanism and more particularly to such mechanism as applied to fast 5 rotary web printing presses, although the invention has other applications in web and sheet handling machines.

Objects and advantages of the invention will be set forth in part hereinafter and in 10 part will be obvious herefrom, or may be learned by practice with the invention, the same being realized and attained by means of the instrumentalities and combinations pointed out in the appended claims.

15 The invention consists in the novel parts, constructions, arrangements, combinations and improvements herein shown and described.

The accompanying drawings, referred to 20 herein and constituting a part hereof, illustrate one embodiment of the invention, and together with the description, serve to explain the principles of the invention.

25 Of the drawings:

Fig. 1 is a fragmentary elevation, partly diagrammatic and with certain old parts omitted, illustrating one embodiment of the invention; and

30 Fig. 2 is a vertical transverse section taken through the central part of Fig. 1;

Fig. 3 is a section taken on line 3—3 of Fig. 1; and

35 Figs. 4 to 7 are diagrams showing several of the optional manners in which the mechanism can be operated.

This invention is directed to providing a 40 novel and useful sheet cutting, collecting, associating and folding mechanism which is capacitated, amongst other things, to handle a product of extraordinary size, that is a very large number of sheets at high speed; the necessity for this arising, and the invention finding one of its most valuable applications in fast rotary printing presses. By my invention a plurality of running longitudinally folded webs are cut into sheets by a plurality of cutting mechanisms, the sheets then being associated and usually collected also, and thereafter folded as an entirety, and thereby the capacity of a printing press, or

other web-using machine is greatly increased. Optionally the plurality of longitudinally folded webs can be cut into sheets by a plurality of cutting mechanisms, collected if desired and thereafter folded to form distinct 55 and separate products from each of the groups of webs.

Furthermore, the mechanism is capacitated to deliver a large variety of lesser products, and to provide different arrangements or associations of the parts of the product with a minimum amount of effort or preparation and of arrangement of the mechanism. For example, if colored webs, or a part web, is run, it may be associated and interfolded in 60 a number of different ways not possible with the usual and known mechanisms.

Another feature of my invention is the provision of optionally operable transfer mechanism between the folding cylinders for 65 transferring unfolded sheets from one folding cylinder to the other and associating these sheets with those on the other cylinder prior to folding.

In the exemplary and present preferred 70 embodiment, broadly defined, two formers are employed, which usually receive the respective halves of a slit web, or any number of running webs associated at the head of the former in the usual manner. Angle bars 75 may likewise be employed if so desired, but usually will not be necessary.

The associated and longitudinally-folded 80 running webs are led from one of the formers to a cross-folding cylinder, which is provided with cutting means. In operative relation with the cross-folding cylinder is a cylinder which cooperates to cut off the sheets, and it may be used optionally to collect 85 one group of sheets, which are then associated with the next group of cut-off sheets 90 upon the cross folding cylinder.

The associated and longitudinally folded 95 running webs from the other former go primarily to a cutting and folding cylinder, and cooperating with this folding cylinder is another cutting cylinder, which also may be used optionally as a collecting cylinder. When so used the first group of sheets cut 100 from the running webs by these cylinders is

collected upon the collecting cylinder, and is then associated with a second cut-off group of sheets upon the folding cylinder. The sheets from the folding cylinder, whether 5 collected or not, are transferred and associated with, the sheets upon the cross-folding cylinder (which may have been collected or not as already described).

The entire group of sheets is then folded 10 off from the cross-folding cylinder in the usual manner, except that provisions are made for handling the very large product which this mechanism renders possible. For this purpose, the forward or right-hand 15 folding-off roller may be lowered as a new lead end of the associated sheets comes by to permit clearance for the lead or head end of the sheets and for the impaling pins. The folding rollers are also longitudinally 20 grooved so as to have a clinching or gripping action upon the fold as the sheets are thrust between them by the folding blades.

In the present embodiment there is provided a transfer cylinder, interposed between 25 two folding cylinders, which is optionally operable and serves to transfer unfolded, collected or uncollected sheets from one folding cylinder to the other, and means are provided for variably positioning the 30 transfer cylinder with respect to the folding cylinders in accordance with the thickness and number of sheets transferred by it and the number and thickness of the sheets collected or carried by the folding cylinder to 35 which the sheets are to be transferred, thereby enabling the mechanism to be adapted to a greater variation in the bulk of the product.

When the transfer mechanism is silenced, 40 the folding and collecting cylinders operate in the usual and well known manner, folded products being delivered by each of the folding cylinders.

Preferably, the sheet cutting and collecting mechanisms are so constructed and arranged with respect to their respective folding cylinders that the cutting is effected non-concurrently and this is preferably carried out by mechanism of the general type more 45 fully shown and described in the application of Harvey D. Bell, Ser. No. 183,280, filed April 13, 1927, now Patent No. 1,720,529, July 9, 1929.

The mechanism also preferably, but not 55 necessarily, embodies the movable folding rollers as set forth in the said application of Harvey D. Bell, so that the forward folding roller is or may be positioned farther from the folding cylinder than its mate to facilitate 60 the handling of the relatively thick and bulky products produced by present construction.

Referring now in detail to the embodiment 65 of the invention illustrated by way of example in the accompanying drawings, the invention is considered applied to a fast rotary

printing press having a plurality of protecting units, the full-width, perfected webs from the various units being brought together at the rollers at the head of the two formers, which latter are fragmentarily shown in Fig. 70 1. Slitting means for the webs are provided, and may be located at and between the formers in a well-known manner.

Former 1 has the usual forming rolls 2 and 3 and guide rolls 4 and 5, the running 75 half web being associated and longitudinally folded at this point. They pass thence about the gripping and alining roller 6 which may be of the usual form. For effecting register or alinement of the web leads and sheets, as shown, shaft 7 of this roller is mounted in arms 8 and 9, which are pivoted upon a shaft 10 carried on the press frame. The screw-threaded adjustment 11 is provided whereby the position of the roller 6 may be varied to 80 register the web leads and sheet heads with the subsequently operating mechanism.

The cross folding cylinder 25 may be of usual or other suitable construction and is shown with its shaft 26 journaled at 27 in the 90 side frames of the press. The cylinder is shown provided with two folding blades 28 and 29, mounted diametrically opposite on the cylinder in a well-known manner. The operating mechanism for the folding blades 95 is not shown, and may be of the standard "Husby" type used on the Goss printing press, or may be of the gear-actuated type.

The folding cylinder 25 as embodied, is provided with two sets of impaling pins, one 100 set 31 being mounted upon corresponding arms 32, fixed on a shaft 33, journaled in the heads of the folding cylinder, the pins being projectable and retractable through holes near the cutting block 57 so as to take and 105 release the sheet heads in the usual manner.

The shaft 33 projects through the cylinder end, and is provided with actuating and timing means, comprising an arm 34 fixed to the shaft 33, and provided with a cam-roller 35, 110 running in the groove cam 36, journaled loosely on the cylinder shaft 26.

The other set of impaling pins 49 is of similar construction, being mounted upon a series of arms 50, fixed to a shaft 51, journaled diametrically opposite in the folding cylinder. The end of this shaft likewise projects from the cylinder end, and fixed to the shaft is an arm 52, carrying a cam-roller 53, which also runs in the grooved actuating 115 and timing cam 36.

The grooved cutting blocks 57 and 58 are oppositely mounted in the folding cylinder in the proper contiguous relations to the impaling pins, and their cooperating cutting 120 blades.

The cutting cylinder 69, which cooperates with the folding cylinder, has its shaft 70 mounted in bearings 71 in the press frame. This cylinder is provided with a cutting blade 130

72, which cooperates successively with the cutting grooves 57 and 58 in the cross-folding cylinder, to cut off two groups of sheets for each revolution of the folding cylinder, the cutting cylinder making two revolutions for one of the folding cylinder. The optionally utilized collecting means comprises a set of impaling pins 75 reciprocable in holes in the collecting cylinder contiguous with the cutting blade 72. These impaling pins are preferably mounted on a corresponding series of arms 76, fixed on a shaft 77, journaled in the ends of the cutting cylinder.

The actuating means comprises an arm 78, fixed to the end of the shaft 77, which projects from the head of the cylinder 69. This arm is provided with a cam-roller 79, running in the groove cam 80, which is mounted on the shaft of the cylinder 69, and may be provided with timing means of any suitable kind, as for instance, like that already described for the impaling pins of the cross-folding cylinder. When the cylinder is not used for collecting, the impaling pins are retracted and silenced in any suitable manner, as for instance by sliding the arm 78 along the shaft 77 and thereby moving the cam roller 79 out of the cam 80.

Referring now to the other series of webs, the associated half webs run down and are longitudinally folded by, the former 100, forming rolls 101 and 102, and guiding rollers 103 and 104 cooperating therewith in the usual manner. The folding cylinder 121 has its shaft 122 mounted in journal bearings 123 in the machine frame and is provided with grooved cutting blocks 135 and 136 diametrically opposed to each other. Folding cylinder 121 is also provided with folding blades 130 and 131. Adjacent to and cooperating with the cutting block 135 is a series of impaling pins 137, which are fixed upon corresponding arms 138, which are fixed to a shaft 139, journaled in the heads of the folding cylinder 121. These pins are in position relatively to the cutting block 135 so as to take the heads or lead of the cut-off webs. The actuating mechanism therefor comprises an arm 140, fixed to the end of the shaft 139, exteriorly to the cylinder, the arm carrying a cam-roll 141, which runs in a groove cam 142, loosely mounted upon the shaft 122 of the cylinder.

The other set of impaling pins 149, cooperates in like manner with the cutting groove 136. These pins are fixed to a corresponding series of arms 150, fixed to a shaft 151, journaled in the heads of the cylinder. An actuating arm 155 is fixed to the external end of the shaft 151 and is provided with a cam-roller 156, running in the groove cam 142.

Cooperating with the folding cylinder 121 is a cutting cylinder 169, which has its shaft 170 journaled at 171, in the side frames of the press. This cutting cylinder is similar

in construction to cutting cylinder 69, and is provided with a cutting knife, cooperating successively with cutting groove blocks 135 and 136, and the cutting cylinder makes two revolutions for each revolution of the cross-folding cylinder 121.

The optionally used collecting means comprises a set of impaling pins 173, reciprocably mounted in cutting cylinder 169 adjacent to the cutting knife to take the web leads. These pins 173 are pivotally connected to corresponding series of arms 176, which are fixed to a shaft 177 journaled in the heads of the collecting cylinder. Actuating mechanism for the pins is provided and may be similar to that shown in connection with cylinder 69.

Similarly, folding cylinder 121 is provided with cooperating folding rollers 207 and 208, similar in construction and operation to folding rollers 199 and 200 and cooperate with folding blades 130 and 131.

According to the present invention there is provided transfer means cooperating with the folding cylinders optionally operable to transfer the collected or uncollected sheets on one folding cylinder to the other folding cylinder where these sheets are associated with other collected or uncollected sheets on the other folding cylinder, after which transfer operation, the associated sheets are simultaneously folded off to form a single product comprising a plurality of, preferably four, sections. In the present embodiment this transfer mechanism comprises a transfer cylinder 220, preferably of the same diameter as the folding cylinders, and provided with two series of impaling pins 221 and 222 fixed on arms 223 and 224. Arms 223 and 224 are fixed to shafts 225, 226 journaled in the heads of the transfer cylinder 220 and the pins are so positioned as to take the heads or lead ends of the sheets on folding cylinder. The actuating mechanism for the pins comprises arms 227, 228 fixed on the end of shafts 225 and 226, exteriorly of the cylinder 220, the arms carrying cam rollers 229, 230 which run in a groove cam 231 loosely mounted on shaft 232 of the cylinder.

Preferably, the transfer cylinder 220 is so constructed and journaled that it can be variably positioned with respect to the folding cylinders to compensate for the various thicknesses and numbers of sheets to be carried by the transfer cylinder, and also to compensate for the different number and thickness of the sheets carried on folding cylinder 25, and as embodied, this transfer cylinder is rotatably mounted in eccentric bushings 236, at each of its ends, and these journals are, in turn, rotatably mounted in bearing blocks 237, slidable on the machine frame. For minutely varying the position of the transfer cylinder and retaining it in the desired position there are provided screws 238, threaded in depending

130

lugs 239 on the machine frame, which serve to vary the distance of the transfer cylinder 220 from the folding cylinder 25. Eccentric bushings 236 have gear segments 240 rigidly 5 fixed to them, meshing with a pinion 241 on shaft 242 rotatably mounted in journals on the machine frame. Hand wheel 243 fixed to shaft 242 is provided for turning the pinions and the eccentric journals. By use of these 10 two means for moving cylinder 220, the distance of the transfer cylinder from each of the folding cylinders can be varied as desired.

Means are also provided for insuring the 15 retention of the sheets on some of the several cylinders as due to the great bulk of the collected sheets, there is a tendency, at times, for the outside sheets to become free of the impaling pins. As embodied, there are provided 20 a plurality of retaining shoes or guides 250 having concave faces concentric with the axis of the cylinders about which they are placed, and these guides are provided around the cylinders at such places as the heads of the sheets 25 might tend to become detached from the impaling pins. In the present embodiment, these guides 250 are shown on the folding cylinder 121 between the collecting cylinder 169 and the folding roller 208; on the transfer 30 cylinder 220 between the folding cylinders 25 and 121; and between folding roller 207 and transfer cylinder 208.

Figures 4 to 7 show, in a diagrammatic manner, certain of the possible optional operations of which the foregoing mechanism is 35 capable.

In Figure 4, the transfer cylinder 220 and the collecting action of the impaling pins on the cutting cylinders 69 and 169 have 40 been silenced. With the mechanism in this condition, the two groups of longitudinally folded webs are led to the cross-folding cylinders 25 and 121 from the formers 1 and 100. The lead ends of the webs have been 45 caught by impaling pins 31 and 137 and on a slight further rotation of the folding cylinders the webs will be cut into sheets by the knives on cutting cylinders 69 and 169 and the new lead ends of the webs will be impaled by pins 49 and 149. The cut sheets on the folding cylinders will then be pushed out at their mid-point into the bight of folding rollers 199 and 200, and 207 and 208 by 50 folding blades 28 and 181 respectively. In 55 this manner each of the folding cylinders delivers two folded products each revolution.

In Figure 5, the collecting mechanism is 60 silenced, and the transfer cylinder 220 has been placed in operation to transfer sheets from folding cylinder 121 to folding cylinder 25. On each half-revolution of the folding cylinders, the webs are cut by the cutter bars on cylinders 69 and 169, the lead 65 ends of the webs are impaled by the pins on

cylinders 25 and 121. As cylinder 121 rotates, the lead end of the web has been carried along by pin 137 until the end contacts with the transfer cylinder 220, at which time, pin 137 is withdrawn, pin 222 is projected to impale the lead end of the web, the leading portion of the web is cut to form a sheet by cutter 160, and the sheet is carried around by a transfer cylinder 220 until it contacts with folding cylinder 25. At this 75 time pin 222 is withdrawn and the sheet is impaled by pin 49 which has already impaled a sheet on cylinder 25. On further rotation, the two superposed sheets, or groups 80 of sheets, are folded between rollers 199 and 200 by folding blade 29. In this way, no sheets are folded off cylinder 121, and two products, each consisting of two sheets or 85 groups of sheets, are folded off cylinder 25 each revolution, giving products comprising 90 two interfolded sections, each of which may comprise a group of sheets.

Figure 6 shows the transfer cylinder 220 silenced, and pins 75 and 173 on cylinders 69 and 169 operating to collect sheets on the 95 folding cylinders 25 and 121. Under these conditions, each of the folding cylinders acts as a separate and independent mechanism cooperating with its own collecting and cutting cylinder. As shown, the lead of the 100 web is first taken by the impaling pins on the collecting cylinder, and the web is wrapped around the collecting cylinder. After the collecting cylinder has made one full revolution, the impaling pin 173 or 75 is retracted, and impaling pin 31 or 149 on the folding cylinder 25 or 121 pierces the web, takes the lead end of the web on the collecting cylinder, and the cutter bar 160 or 72 cuts the web, allowing the folding cylinder 105 to rotate carrying the lead end of the sheet superposed on the lead end of the web. After a half revolution, cutter bar 160 or 72 cuts the web forming two sheets on the folding cylinder which are then folded 110 off by blade 180 or 29 and the lead of the web is transferred to pin 173 or 75. Whenever the collecting mechanism is in operation, one half of each folding cylinder carries no sheets, one folding blade and one set of impaling pins, for each folding cylinder, is silenced. This manner of operation results 115 in the production of one interfolded product comprising two sections of longitudinally folded sheets, or groups of sheets, each 120 revolution of each folding cylinder.

In Fig. 7, the collecting and transfer mechanisms are in use and the operations 125 shown in Figs. 5 and 6 are combined producing a single product comprising four interfolded sections, each comprising a sheet or group of sheets, each full revolution of both folding cylinders. The sheets are collected on the folding cylinders in the manner shown in Figure 6, the folding mechanism 130

for cylinder 121 being entirely silenced, and the collected sheets or groups of sheets on cylinder 121 are transferred to the transfer cylinder 220, as described in detail with respect to Fig. 5. Transfer cylinder 220 transfers the two groups of sheets to folding cylinder 25, where they are associated with two groups of sheets on this folding cylinder and all four groups are folded off together between the folding rollers 199 and 200, as a single product of four sections.

If desired, the perfecting units of the press, perfecting the webs which are to form the outside sections of the paper, can be clothed rather heavily, the other units being normally clothed, thereby increasing the speed of the webs for the outside sections.

The foregoing describes some of the principal manners in which the mechanism can be operated, and the other manners of operation will be clear to those skilled in the art from this disclosure of the invention.

The invention in its broader aspects is not limited to the specific mechanisms shown and described but departures may be made therefrom within the scope of the accompanying claims without departing from the principles of the invention and without sacrificing its chief advantages.

30. What I claim is:—

1. A sheet cutting and handling mechanism including in combination means for longitudinally folding a plurality of groups of webs, means for cutting the webs into sheets, optionally operable means for collecting the sheets from each group of webs, optionally operable means for associating unfolded sheets from one group of webs with sheets from another group of webs and optionally operable means for folding the sheets from each group of webs separately or for folding the associated sheets.

2. A sheet cutting and handling mechanism including in combination means for cutting webs into sheets, optionally operable means for collecting the sheets from each group of webs, optionally operable means for associating unfolded sheets from one group of webs with sheets from another group of webs and optionally operable means for folding the sheets from each group of webs separately or for folding the associated sheets.

3. A sheet cutting and handling mechanism including in combination means for longitudinally folding a plurality of groups of webs, means for cutting the webs into sheets, means for collecting the sheets from each group of webs, optionally operable means for associating unfolded sheets from one group of webs with sheets from another group of webs and optionally operable means for folding the sheets from each group of webs separately or for folding the associated sheets.

4. A sheet cutting and handling mecha-

nism including in combination means for longitudinally folding a plurality of groups of webs, means for cutting the webs into sheets, optionally operable means for collecting the sheets from each group of webs, means for associating unfolded sheets from one group of webs with sheets from another group of webs and optionally operable means for folding sheets from each group of webs separately or for folding the associated sheets.

5. A sheet cutting and handling mechanism including in combination means for longitudinally folding a plurality of groups of webs, means for cutting the webs into sheets, optionally operable means for collecting the sheets from each group of webs, optionally operable means for associating sheets from one group of webs with sheets from another group of webs and optionally operable means for folding the sheets from each group of webs.

6. A sheet cutting and handling mechanism including in combination means for longitudinally folding a plurality of groups of webs, means for cutting the webs into sheets, optionally operable means for collecting the sheets from each group of webs, means for associating sheets from one group of webs with sheets from another group of webs and optionally operable means for folding sheets from each group of webs.

7. A sheet cutting and handling mechanism adapted to operate on a plurality of groups of webs including in combination means for cutting webs into sheets, means for collecting the sheets from each group of webs, means for associating sheets from one group of webs with sheets from another group of webs and optionally operable means for folding sheets from each group of webs.

8. A sheet cutting and handling mechanism including in combination means for longitudinally folding a plurality of groups of webs, means for cutting the webs into sheets, means for collecting the sheets from each group of webs, optionally operable means for associating sheets from one group of webs with sheets from another group of webs and optionally operable means for folding the sheets from each group of webs.

9. A sheet cutting and handling mechanism including in combination a folding cylinder, a collecting cylinder optionally operable to collect sheets on the folding cylinder, a transfer cylinder cooperating with said folding cylinder, a fourth cylinder, a collecting cylinder optionally operable to collect sheets on the transfer cylinder, and means for silencing said folding cylinder and transferring the sheets to the fourth cylinder.

10. A sheet cutting and handling mechanism including in combination a folding cylinder, a collecting cylinder optionally operable to collect sheets on the folding cylin-

der, a transfer cylinder cooperating with said folding cylinder, a fourth cylinder optionally cooperable with the transfer cylinder to receive sheets from the transfer cylinder, 5 means for folding sheets from the fourth cylinder and means for collecting sheets on the fourth cylinder.

11. A sheet cutting and handling mechanism including in combination a pair of 10 folding cylinders for folding sheets cut from webs, a collecting cylinder for each folding cylinder optionally operable to collect sheets on the folding cylinders, a transfer cylinder between the folding cylinders to transfer 15 sheets from one folding cylinder to the other.

12. A sheet cutting and handling mechanism including in combination a pair of folding cylinders for folding sheets cut from webs, a collecting cylinder for each folding 20 cylinder optionally operable to collect sheets on the folding cylinders, a transfer cylinder between the folding cylinders to transfer sheets from one folding cylinder to the other, and means for moving the transfer cylinder 25 toward and from the folding cylinders to accommodate a different number of sheets.

13. A sheet cutting and handling mechanism including in combination a pair of folding cylinders for folding sheets cut 30 from webs, a collecting cylinder for each folding cylinder optionally operable to collect sheets on the folding cylinders, an optionally operable transfer cylinder between the folding cylinders to transfer sheets from 35 one folding cylinder to the other.

14. A sheet cutting and handling mechanism including in combination a folding cylinder, a collecting cylinder optionally operable to collect sheets on the folding cylinder, 40 a third cylinder optionally operable to supply sheets to be transferred to the folding cylinder or to fold a group of sheets, and a collecting cylinder optionally operable to collect sheets on the third cylinder.

45 15. A sheet cutting and handling mechanism including in combination a folding cylinder, a collecting cylinder optionally operable to collect sheets on the folding cylinder, a transfer cylinder cooperating with said 50 folding cylinder, a fourth cylinder optionally operable to supply sheets to the transfer cylinder to be transferred to said folding cylinder or to fold a group of sheets and a collecting cylinder optionally operable to 55 collect sheets on the fourth cylinder.

16. A sheet cutting and handling mechanism including in combination a pair of folding cylinders, a transfer cylinder interposed between them to transfer sheets from one 60 folding cylinder to the other, and means for variably positioning the transfer cylinder for different thicknesses of products.

17. A sheet cutting and handling mechanism including in combination a pair of folding cylinders, a transfer cylinder interposed

between them to transfer sheets from one folding cylinder to the other, an eccentric mounting for the transfer cylinder and a 70 slidable member in which the eccentric is mounted.

18. A sheet cutting and handling mechanism including in combination a plurality of formers for longitudinally folding a plurality of webs, a plurality of folding cylinders, an optionally operable transfer means 75 to transfer sheets from one folding cylinder to another, and means for non-simultaneously cutting the webs into sheets.

In testimony whereof, I have signed my name to this specification.

ERNEST JAMES SMITH.
